(57) **CLAIM**

I claim the ornamental design for a boot cover with pockets, as shown and described.

DESCRIPTION

FIG. 1 is a front and left side elevation perspective view of the boot cover with pockets, mounted in place on a boot;
FIG. 2 is a rear and right side elevation perspective view of the boot cover with pockets, mounted in place on a boot;
FIG. 3 is an outside surface elevation view of the boot cover with pockets;

FIG. 4 is a bottom plan view of the boot cover with pockets;
FIG. 5 is a side elevation view of the boot cover with pockets;
FIG. 6 is an inside surface elevation view of the boot cover with pockets;

FIG. 7 is a top plan view of the boot cover with pockets; and,
FIG. 8 is a side elevation view of the boot cover with pockets. The broken line shown in FIGS 1, 2, 3 and 6 illustrate environmental structure and stitching, and forms no part of the claimed design.
